JACQUARD FOR TERRY LOOMS

Herbert V. Foster, Providence, R. I., assignor to Crompton & Knowles Jacquard & Supply Company, Pawtucket, R. I., a corporation of Massachusetts

Application July 30, 1938, Serial No. 222,184

16 Claims. (Cl. 139—59)

This invention relates to improvements in jacquard mechanism for looms and it is the general object of the invention to provide a jacquard more particularly adapted for the weaving of terry fabrics having figured patterns.

In weaving so-called three pick terry fabrics three beats of the lay and shuttle flights are required to complete one row of tufts across the cloth. The weft is held in a rearward position for the first two picks and then is given a full forward motion with the third pick, the pile warp lying between the picks and the preceding row of tufts being looped when all three picks are beaten up. The loom therefore operates on a three-pick cycle although occasionally so-called four-pick terry's are woven.

When the pile warps and the loops formed from them are controlled so as to produce a fancy pattern it has been customary heretofore to have a separate card on the jacquard for each pick of the loom, necessitating three cards for one row of terry tufts. It is an important object of my present invention to economize on the cards by providing a jacquard so constructed and operated that one card will suffice for the three picks for each row of tufts.

During the weaving of the unfigured body of the fabric half of the loops lie on one side and half on the other side of the cloth, and this result is achieved by dividing the terry forming warp into two sheds the upper of which forms the top tufts and the lower of which forms the bottom tufts. When the figured part of the pattern is woven from warps of the same color, all of the tufts are thrown to one side of the cloth to produce a dense pattern effect which leaves the opposite side of the cloth blank. Another method used preferably where colors are involved reverses the location of the tufts, the blue tufts, for instance, which were on the top of the unfigured part of the fabric are thrown to the bottom, while the corresponding white tufts on the under side are thrown to the top. In this method tufts are formed on both sides and the pattern effect is achieved by a difference of color. My invention to be set forth hereinafter is equally adaptable to the production of either of these types of figured terry fabric.

It is an important object of my invention to provide three sets of hook lifting knives which are so actuated that at any instant in the jacquard operation one knife will be rising, the second knife will be descending, and the third knife will be stationary, each knife in its turn at three-pick intervals rising for one pick, then falling

for one pick, and then dwelling stationary for one pick.

It is another object of my present invention to provide two lifting jacks for each lifter cord and form one of said jacks with oppositely facing hooks so that the pair of jacks present three hooks, one for each knife. Each pair of hooks is controlled by a single needle the positions of which is determined by a card of the jacquard and a single hole punched in the jacquard card will suffice to give indication for three consecutive picks.

It is still another object of my present invention to provide mechanism for reversing the movement of the knives and the jacquard cylinders to permit the removal of a defective pick in the fabric. The driving mechanism for the knives is so constructed that reversal of the driving mechanism causes the knives to operate in the reverse order.

The fact that the jacquard operates to produce a complete row of tufts from one card makes possible the use of one card to produce an area of plain or unpatterned terry tufts and it is a further object of my invention to combine the jacquard with a multiplier to be set forth in detail hereinafter and effective when called at the end of a figured pattern to render the cylinder turning pawl inoperative and thereby maintain a single card in control of the jacquard during the weaving of a block of plain terry loops.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a side elevation of the upper part of a loom having attached thereto a jacquard made according to my present invention.

Fig. 2 is an enlargement of a portion of the upper part of Fig. 1, showing the cylinder operating mechanism.

Fig. 3 is a vertical section on line 3—3 of Fig. 1.

Fig. 4 is an enlarged side elevation of the upper part of Fig. 1 with the sprocket wheel removed.

cylinder and cards, and the lifter cords, two needles entering holes in a card and two being pushed back by blank places on the card,

Fig. 9 is a diagrammatic view of a weave when 5 the pattern effect is obtained by reversing the location of colored tuft warps from one side to the other side of the fabric,

Fig. 10 is a diagrammatic cross section of the fabric made according to the weave set forth in 10 Fig. 9 after the tufts have been beaten up,

Fig. 11 is a diagrammatic view of a weave in which the patterned effect is obtained by throwing all of the figured terry warps on one side of the cloth,

15 Fig. 12 is a view similar to Fig. 10 but showing the fabric made according to the weave set forth in Fig. 11,

Figs. 13 to 16 are diagrammatic views showing the successive steps in forming a row of terry 20 tufts,

Figs. 17 and 18 show two sets of cards punched to produce the weaves shown in Figs. 9 and 11, respectively.

Fig. 19 is an enlarged detail side elevation of 25 the multiplier mechanism shown in the upper right hand part of Fig. 1, and

Fig. 20 shows a set of cards punched to control the multiplier.

In order that the invention may be more readily understood I will first describe the types of 30 patterned terry fabrics set forth in Figs. 9 and 11. For convenience in illustrating the weave I have shown the picks of filling separated in groups of three, the groups being indicated at I to VII, 35 inclusive, and the picks of each group being indicated at a, b and c, in the order in which they are laid by the shuttle. It is to be understood that there are two different sets of warp threads in terry fabrics, the first of which forms the 40 ground weave and is tight throughout the weaving of the fabric, while the second set is drawn from a different warp beam and is slackened periodically at three-pick intervals to permit the formation of tuft piles. Each of these sets of 45 warp threads is interwoven with the picks of filling, the ground warps having always the same relation with respect to the filling and undergoing no change when the pattern is formed, while the terry set will also sustain the same 50 relationship to the picks of filling while unpatterned terry is being woven, but the terry warps change their relationship with respect to the picks of filling at the beginning and ending of a patterned figure, the relation of the terry warps 55 with respect to the picks of filling being unchanged throughout the weaving of the figures. The jacquard to be described hereinafter controls the terry warps and the usual cam harness mechanism not shown is employed for the weaving 60 of the ground warps.

Referring to Fig. 9, the terry warps 25 and 26 are represented at the left hand of the figure as at the top and bottom, respectively, of the shot of filling Ia. In this type of weave the terry 65 warps may be of different colors, the warp 25 passing under shot Ib and over shot Ic. The lower warp 26 has the opposite relation with respect to these shots and leaves the group I under the warp 25. The space between shot Ic and 70 IIa represents the length of terry warp which is to make the tufts pile. That part of the weave already described constitutes a normal non-patterned part of the fabric before the patterned area is reached.

75 When the location of the terry warps is to be

reversed the relation will be that shown in group III. The relation of terry warps in this group will be the reverse of that shown in group I, the upper warp 25 passing under shot IIIa, after which its relationship with respect to the shots of filling in group III will be as indicated, the length of terry warp 25 between shot IIIc and IVa from which the terry tuft is formed being now on the under side of the fabric. In a similar manner the terry warp 26 is on the top of the 10 fabric. The interweaving of the groups IV and V will be similar to that of group III, and it is to be understood that there will be as many groups similar to IV and V as are required by the figure being woven.

When the terry 25 is to be returned to the top of the fabric the relationship will be that shown in group VI where warp 25 is raised to lie over shot VIa, this marking the end of the pattern figure, after which the relation between the 20 shots of filling and the two sets of terry warps will be the same as that described for the group I. When all the loops are formed in the fabric they will appear as suggested in Fig. 10 where the two upper left hand tufts are formed from warp 25, the next upper three reading to the right being formed of warp 26, while the remainder of the upper tufts are again formed of the set 25. The reverse pattern effect appears on the bottom of the cloth.

Referring to Fig. 11, the upper and lower terry warp threads 27 and 28 at the left hand end sustain the same relation to the shots of group I and II as in the previous weave, but in this instance the set 28 remains unchanged throughout 30 the weaving of the pattern, being the same for both the body and pattern, the warp 28 passing over the center shot of each group and under the other two. The warp 28 is therefore not necessarily controlled by the jacquard since it 35 has a simple invariable three-shot cycle, and a three pick cycle cam harness mechanism as commonly used may be employed.

The other warp 27, however, is changed so that at times it is on the upper part of the fabric, as suggested at the left and right hand ends of Fig. 11, and at other times parallels the warp 28 45 as suggested in the intermediate part of said figure to form the pattern. Under these conditions warp 27 will be controlled as is warp 25.

The fabric produced by the weave shown in Fig. 11 is set forth in Fig. 12 where the right and left hand ends of the fabric have piles on both sides, whereas the intermediate portion has all of the piles thrown to the under side, the upper 50 part being blank to form the pattern.

It will be seen by referring to Figs. 9 and 11 that the upper set of warps starting at the left hand end indicated at 25 and 27 undergo a change when the pattern is reached and also when it is concluded and that in Fig. 9 the lower warp 26 has a similar but opposite relationship. In order to simplify the description the mechanism will be described as though it were to weave the fabric shown in Fig. 11, but it will be understood that the jacquard cards can be punched to produce the weave of Fig. 9, as will be set forth herein-after.

Referring more particularly to Fig. 1, I have shown a loom frame 30 having a lay 31 and a 70 reed 32 which is given two relative settings with respect to the lay by means of mechanism such as that shown in Patent No. 2,082,888. This mechanism is well known and is thought to need no further description other than to say that the 75

first two picks of a cycle are beaten up to a position behind the fell, as in Figs. 13 and 14, while the third pick is beaten up to the first two as in Fig. 15, and then on the same beat all three shots are beaten to the fell of a cloth, thereby bending the terry warps to form tufts. The lay may be driven by the usual connector 33 actuated by the top or crank shaft 34 of the loom.

The jacquard J comprises cross timbers 35 mounted on uprights 36 supported from the floor and has a frame 37 and a card rack or guide 38. I provide three sets of vertically reciprocating knives indicated at 41, 42 and 43, each set comprising several knives which move together. The knives 41 are carried by a rack 45 which is raised and lowered by links 51 adjustably connected to vertically rocking levers 61. The levers 61 are driven by cams 71 fixed to a shaft 46 journaled in an auxiliary frame 40 on the timbers.

Knives 42 are carried by a rack 47 connected by links 52 to levers 62 which are rocked by cams 72 secured to shaft 46. The third set of knives 43 is mounted on the third rack 48 which is reciprocated vertically by links 53 connected to driving levers 63 which are reciprocated vertically by cams 73 fast on the shaft 46. Vertical guide rods 49 are provided for the several racks and supported by the frame of the jacquard to require the knives to move vertically in fixed paths as the cams rotate.

Each cam is secured to the shaft 46 which rotates once each three picks of the loom by mechanism to be described and the cams are all alike, each having a driving groove 52 to receive a roll 53 on the lever it drives. Each cam has a low dwell 54 and a high dwell 55, the dwells being connected by inclines 56. The grooves are symmetrical about a diameter and the lines of symmetry of the several cams are spaced 120° apart so that each cam comes to its high position every third pick and one or another of the cams reaches high position each pick.

The low dwells 54 cover approximately 120° around the shaft 46 and cause a low dwell of the corresponding knives for one pick of the loom. The levers 61, 62 and 63 are all pivoted as at 50 to a fixed axis supported by the auxiliary frame 40. From the mechanism thus far described it will be understood that a complete rotation of shaft 46 will cause the sets of knives to move as previously indicated, that is, one set will be moving up while another set will be moving down and the third set will be dwelling in low position.

Rotation of shaft 46 is accomplished by the mechanism shown in Fig. 1 which includes a sprocket gear 65 fastened to the shaft 46 and driven by a chain 66 trained around a sprocket 67 fast with a gear 68 mounted on a stud 69 supported by the loom frame. A second gear 70 meshes with and is the same size as gear 68 and rotates with a sprocket 75 having driving connections by means of chain 76 with a sprocket 77 on the crank shaft 34. Rotation of the crank shaft therefore causes rotation of the gears 68 and 70 which in turn drive the sprocket 65. The latter is three times the diameter of the sprockets 67 and 75 which are equal, by which relation the shaft 46 is given one complete rotation for each three rotations of the shaft 34.

A hand wheel 78 is cast integral with the sprocket 77 and has a hub 79 freely rotatable on the shaft 34. An arm 80 has a spring plunger 81 provided with a hand hold 82 by which the plunger may be moved outwardly against the

action of spring 83. The plunger head fits into a bore 84 in the hand wheel and the arm is keyed as at 85 to the shaft 34. When the plunger is in the position shown in Fig. 3 the sprocket 77 is driven by shaft 34, but when the hand hold 82 is pulled out to disconnect the shaft 34 and arm 80 from the hand wheel, the latter can be rotated to turn the sprocket 77 independently of the loom, thereby causing rotation of shaft 46 while the loom is at rest. The purpose of this mechanism is to permit the weaver to correct a miss-pick by finding the proper shed in which the miss-pick occurred through operation of the hand wheel 78 independently of the loom, after which the plunger 81 is returned to normal position to establish driving connection between the shaft 34 and the sprocket 77.

The card cylinder is operated by a fourth cam 90 secured to shaft 46 and having a groove 91 to receive roll 92 and lever 93 fulcrumed at 54. A bell crank lever 95 moves about a fixed axis 96 has driving connection with lever 93 through an adjustable link 97 and in turn is connected by a second link 98 to a driving head 99 adjustably secured to a rod 100 slidably horizontally on the jacquard frame. The outer end of the rod 100 has provision indicated generally at 101 for supporting rotatably thereon the jacquard cylinder 102. An operating pawl 103, Fig. 4, pivoted at 104 to the jacquard frame has a hooked head 30 105 to engage successively the several pins 106 formed in the corners of the cylinder at one end thereof. The matter just described is of common construction and except for the cam 90 may be made according to accepted practice. 35

The cam 90 has two high points 110 and 111 with a low intermediate run 112 connecting these points on one side of the shaft 46 and a still lower run 113 on the opposite side of the shaft. When the roll 92 approaches one of the high points the parts are rocked in such a direction as to move the cylinder 102 to the left or in toward the needles 115 and when run 112 is occupied by the roll 92 the cylinder is moved away from the needles a slight amount not sufficient however to cause engagement of the pawl 103 with one of the pins 106. As the cam moves in the direction of the arrow Fig. 2, the other high point then operates to move the cylinder back toward the needles, after which the low run 113 comes into play to move the cylinder at its maximum distance away from the needles and cause turning of the cylinder by the pawl 103 in well-known manner.

The cylinder has trained thereover a series of jacquard cards C', C², C³, etc., which are presented to the needles one at a time every third pick of the loom by the mechanism just described and shown in Fig. 2. These cards are shown in more detail in Figs. 17 and 18.

Fig. 8 shows four needles each controlling a pair of jacks together with four sets of knives. It will be understood that the jacquard will have a number of needles and pairs of jacks depending upon the number of terry warps to be controlled, but this description will be limited to the needle and jacks which control the terry warps of one longitudinal row of terry tufts, it being understood that the remaining needles and jacks will operate in a similar manner.

As shown in Fig. 8 each group of three knives is associated with two upright jacks 118 and 119, the first jack having a hook 121 for engagement with knife 41 while the second jack 119 has hooks 122 and 123 for engagement with knives 75

62 and 43, respectively. The hooks 122 and 123 point in opposite directions and are so related that when one of them lies in the path of the knife corresponding thereto the other hook will 5 be out of the path of its knife so that but one of the knives 42 or 43 is able to lift jack 119 at a time.

The lower end of each jack is provided with a 10 supporting hook 125 which rests on a stationary plate 126 and a link 127 connects the bottoms of the two jacks to a lifter cord 128. When one of the jacks is raised the link 127 moves upwardly therewith to elevate the cord 128 and slides along the bent lower part 129 of the unraised jack.

15 Each needle 115 has a pair of loops 130 by which it controls the pair of the jacks 118 and 119 and has the usual spring 131 to hold the needle in normal out position with the hooks 121 and 123 in the paths of their knives 41 and 43, 20 respectively, while hook 122 is out of the path of its knife 42. This relation is shown at the right hand pair of jacks in Fig. 8. When the needle is pushed in or moved to the left as viewed in Fig. 8 both jacks controlled thereby change 25 their relative position with respect to the associated knife, hooks 121 and 123 moving clear of their knives while hook 122 is placed over its knife 42.

In describing the operation of the jacquard it 30 will be convenient to bear in mind that a punched hole in the card has the same effect on needle 115 as though the card were not in indicating position, such as would be the case if the cylinder were moved out to be operated by the pawl 103, and it is also convenient to remember that after knife 42 has engaged hook 122 when rising the position of hook 123 will be determined independently of the card until knife 42 descends to a point where it can release hook 122. The 35 cylinder and card therefore need not be in indicating position during the interval in which the knife 42 is in engagement with hook 122. Each knife rises during one pick and falls during the next pick, and the outward card feeding and return motions of the cylinder occur during the 40 greater part of two picks or beats of the loom.

Considering first the weave shown in Fig. 11 and assuming that a card is presenting a punched hole 27a to needle 115, a knife 41 will rise to 45 lift hook 121 during the descent of knife 43 and thereby raise terry warp 27 for the laying thereunder of shot 1a. Knife 41 then starts down and a knife 42 starts up without engaging hook 122 so that warp 27 will be down and shot 1b can 50 pass over it. As soon as the normal time for engagement of hook 122 by knife 42 is passed in the ascent of knife 42 the cylinder is moved out by decline 113 of cam 90 to be given a quarter turn by the pawl 103.

55 As knife 42 starts down a knife 43 will start up and will engage hook 123, since the latter is normally positioned over knife 43 by the corresponding spring 131, this condition existing when the card is away from indicating position. Warp 27 therefore is raised again for the passage thereunder of filling shot 1c. This sequence continues so long as unfigured terry warps are to be woven by warp 27 and the latter will form terry tufts on the top surface of the fabric. As many unfigured rows of tufts as are needed will be thus formed, one additional row being provided and formed by unit or group II, Fig. 11.

70 During the manipulation of warp 27 just described an opposite control will be exercised for terry warp 28. A blank space 28a on all the

cards shown in Fig. 18, corresponding to the weave of Fig. 11, controls a needle 114 which positions a second pair of jacks 116 and 117 corresponding respectively to jacks 118 and 119. In the sequence for warp 28 a knife 41 will rise without lifting jack 116, a knife 42 will then lift jack 117 and a knife 43 will then rise without effect on jack 117 despite the fact that the cylinder is out because jack 117 is still held to a knife 42. Warp 28 forms the terry tufts on the bottom of 10 the fabric throughout the weave shown in Fig. 11, and a further understanding of the manipulation of warp 28 will be gotten by the description to follow of the manipulation of warp 27 to place its tufts also on the bottom of the fabric. 15

At each complete out motion of the cylinder a new card will be placed in controlling position facing the needles. Cards C', C2 shown in Fig. 18 are punched with holes 27a and left blank at 28a to produce the manipulations of warps 27 and 20 28, respectively, as shown in groups I and II, Fig. 11.

It is assumed that the figured pattern will start at group of shots III, Fig. 11, in which case card C3, Fig. 18, will have that part thereof controlling needle 115 left blank at 27b, and as high point 110 of cam 90 moves the cylinder in to place this card in indicating position, hook 121 will be moved out of the path of knife 41. Knife 41 therefore rises without lifting warp 27 and 30 the latter will be under shot IIIa. During up motion of knife 41, however, knife 43 is descending and in engagement with hook 123 from the previous cycle, and jack 119 is therefore under a strain from needle 115 tending to bend it to 35 the left as viewed in Fig. 8. In order to relieve this strain the cylinder is backed off slightly by run 112 of cam 90 as soon as the normal time for engagement of hook 121 by knife 41 during ascent of the latter has been passed. This backing off of the cylinder, which occurs once for each three pick cycle of the loom is not enough to cause turning of the cylinder by pawl 103. Knife 43 reaches its low position and therefore 40 loses control of hook 123 before knife 42 starts up. High point 111 of cam 90 now returns the cylinder and card to the left as viewed in Fig. 4 to give an indication for hook 122 just prior to rising of knife 42. Knife 42 will then raise hook 122 and warp 27 will be above shot IIIb. 50 The cylinder is moved all the way out by decline 113 of cam 90 to cause turning by pawl 103 to place the next card in controlling position.

Knife 42 now holds both hooks 122 and 123, and as previously described, this will determine 55 the position of hook 123 on the next pick. As knife 43 ascends hook 123 will be held out of its path by hook 122 and knife 42 and warp 27 will therefore be down at the end of the up motion of knife 43 so that shot IIIc can pass over warp 27. 60 This places warp 27 in the bottom shed and its tuft loops will be on the underside of the fabric along with those of warp 28 to form the pattern. As many such cycles are repeated as the pattern demands, units or groups IV and V being 65 shown as similar to group III.

When the figure is completed, as at group VI, card C6 then in control will present a hole to needle 115, and the relation of warp 27 to the shots VIa and VIb and VIc will be as described 70 in connection with group I. Warp 27 is thereafter restored to the top shed to form tufts on the upper side of the cloth, and the figure, so far as warp 27 is concerned, is completed. An additional card C7 is shown to form group VII which 75

with group VI, starts the weaving of unpatterned fabric.

Fig. 12 shows the tufting of the fabric woven as indicated in Fig. 11 and suggests that the pattern is formed by the production of a blank space on one side of the cloth, the tufts on the opposite sides of the blanks being of double density. When the pattern is to be formed as suggested in Figs. 11 and 12, therefore, there will be no change in the several cards with respect to their control of the lower tuft forming warp 28, and the variation in the punching of the cards will come only with respect to the control exercised by the cards on warp 27.

Turning now to the fabrics set forth in Figs. 9 and 10 it will be seen that warp 25 is controlled in a manner exactly similar to that already described for warp 27. Warp 26 normally forming the bottom tufts, however, is controlled the same as that of warp 25 except in reverse direction, and wherever the cards have a hole punched for the lifting of warp 25 there will be a corresponding blank for lowering the warp 26, inasmuch as these two warps 25 and 26 are always on opposite sides of any given shot of filling. In this instance the pattern is produced by a color change, warp 25 being one color while warp 26 is of a different color, and there will be tuft loops on both sides of the fabric throughout the length of the pattern.

Fig. 17 shows a series of cards which will produce the weaves found in Fig. 9. In these cards it is assumed that the upper left hand corner of each card is reserved for the control of the warp thread which normally provides the top tufts in an unfigured part of the cloth and that the lower left corner controls the warp threads normally forming the bottom tufts. In Fig. 17 card K' corresponds to the group of shots I, Fig. 9, and the perforation 25a causes lifting of warp 25 over shot 1a, lowering under shot 1b and lifting over shot 1c as did hole 27a for warp 27 in the previous description. Cards K', K2, K6 and K7 have punched holes 25a in their upper left corners, while cards K3, K4 and K5 are blank in that corner, these cards being the same in this respect as the corresponding cards of Fig. 18, and therefore causing warp 25 to be like warp 27.

Warp 26 is disposed as is warp 28 in groups I, II, VI and VII and the corresponding cards K', K2, K6 and K7 are therefore blank in their lower left corners, as are cards C', C2, C6 and C7. In the three shot groups III, IV and V, however, warp 26 is disposed oppositely to the arrangement of warp 28 in the corresponding groups of Fig. 11, and therefore where cards C3, C4 and C5 are blank in their lower left corners, cards K3, K4 and K5 are perforated, see Fig. 17, to cause warp 26 to lie under shots b of groups III, IV and V and over shots a and c of these groups. This arrangement of holes and blanks means that the warps 25 and 26 are always on opposite sides of any given shot of filling, a condition already pointed out as essential to the weave shown in Fig. 9.

When a pick-out is made to correct a mispick in cloth, plunger 81 is pulled out to disconnect shaft 34 from the hand wheel 78 and the latter is then turned backward one revolution at a time each pick being removed as its shed is open. During the pick-out the sheds are opened in an order which is the reverse of that which existed when weaving under power. When the picks controlled by one card are removed the cylinder 102 is turned back by well-known reversing

mechanism shown in Fig. 1 and including a pull cord 180, lever 181 pivoted to the upright 182 moving with the cylinder, and a reversing pawl 183 on lever 181 to be raised when the cord is pulled down to turn the cylinder in a reverse direction. This presents the previously active card in control position, after which the wheel 78 may be given three more revolutions, one at a time. This procedure is followed until the faulty pick is reached, after which the plunger 81 is again caused to establish driving connection between the shaft 34 and the sprocket 77 and weaving will be resumed. By taking out a number of picks which is a multiple of three and by turning the cylinder back a number of cards equal to the multiple or one-third the number of total revolutions of wheel 78, the reed controlling mechanism of the loom, the cylinder motion, and the sequence of lifting motions of the knives are all coordinated and after the take-up has been turned back and the beams for both the ground and terry warps have been turned back the proper amount the loom is in condition for weaving.

All three of the cams 71, 72 and 73, and also cam 90 are symmetrical and may therefore be set to drive the jacquard either in the sequence already described or in the reverse sequence, the cams having their settings altered to produce results similar to those already described when the jacquard is to be driven in reverse order.

The weave shown in Figs. 9 and 11 have been described without particular reference to the ground warps but they have been indicated at W and W' in these figures. It is to be understood that the ground warp is not controlled by the jacquard but by a harness mechanism driven by a cam motion and in the pick-out operation, if a cam harness motion is used, it will be necessary to carry the pick-out far enough to find the correct shed for the ground warps.

Terry units I, II, VI and VII, Fig. 9 produce plain unpatterned rows of shots and since each unit derives its indication from a single card I am able to use a multiplier the effect of which is to maintain a single card in control of the jacquard to produce a plurality of rows of plain terry tufts. This feature of my invention is set forth in Figs. 1, 19 and 20.

The multiplier M is mounted on the cross timbers 35 of the jacquard and includes a stand 140 carrying a shaft 141 to which is secured a chain cylinder 142 and a ratchet wheel 143. A multiplier chain 144 on the cylinder has in the present instance a single small or low roll 145 and a number of large rolls 146. A lever 147 on a fixed pivot 148 has a shoe 149 which rests on and is positioned by the rolls on the chain. An arm 150 of lever 147 is connected to an ascending link 151 attached to a finger 152 on the jacquard cylinder feed pawl 153, which will be similar to pawl 103 but modified by the addition of the finger. A yielding lock roll 154 usual in multipliers is provided to cooperate with a notched wheel 155 fast with shaft 141 and hold the cylinder with either the low or one of the high rolls of the chain under the shoe 149 between the step by step movements of the cylinder.

In order to control and actuate the multiplier chain I provide the jacquard with a multiplier jack 160 preferably in line with one of the jacks 118 and made similar to the latter for cooperation with a knife 41. The lower end of this jack is connected by a link 161 to a lever 162 pivoted

as at 163 to the frame 140. The right end of lever 162 as shown in Fig. 19 is connected by link 164 to a lever 165 mounted loosely on shaft 141 and having pivoted thereon a feed pawl 166 for cooperation with ratchet wheel 143. A tension spring 167 is provided for holding the right ends of levers 162 and 165 elevated so that the pawl 166 will be normally in relative left hand position, as shown in Fig. 19.

16 A needle 170 controlling the jack 160 is positioned for control by the jacquard cards. Certain of these cards, shown in Fig. 20, control the multiplier and will be punched at 25a in their upper left hand corners to produce plain terry, being 17 similar in this respect to other cards in the chain already described. Although I have shown but one perforation 25a, as in Figs. 17 and 18, there will nevertheless be a series of these punchings to control pairs of jacks. The cards for the 20 pattern, as shown in Figs. 17 and 18, will be blank in their upper right corners to push jack 160 out of the path of knife 41.

The first card to control the multiplier, shown at M', Fig. 20, will be punched in its upper right corner at 175 to allow jack 160 to remain in the path of knife 41. The latter will therefore lift jack 160 to turn lever 165 in a right hand direction as viewed in Fig. 19 and give the pawl 166 a right hand feeding motion. Prior to the 30 beginning of this operation the shoe 149 rests on low roll 145 which permits the cylinder pawl 153 to be in the down full line position of Fig. 19, but feeding motion of the pawl 166 turns cylinder 142 clockwise one step to present the first of a 35 series of high rolls 146 under the shoe 149 to raise it.

Lifting of shoe 149 moves lever 147 and cylinder pawl 153 to the dotted line, Fig. 19. Jacquard pawl 153 will be raised to inactive position relatively to the cylinder. As the latter moves outwardly away from indicating position it will not be turned because of the inactive position of pawl 153 and card M' will again be presented to the needle 170, whereupon engagement of jack 160 by the ascending knife 41 in the next cycle will again feed the multiplier cylinder another step to place the next high roll under the shoe 149. This continues until the last high roll has passed from under shoe 149, whereupon low roll 50 145, appearing under the shoe, permits pawl 153 to fall by gravity to feeding position. There will then have been woven as many rows of terry loops as there are rolls in chain 144. The next 55 out motion of cylinder 102 will therefore present a new card to active position.

If enough rows of plain tufts have been woven, this next card will start a new pattern, but if the length of the plain tuft weaving desired is more than can conveniently be taken care of by one 60 card M', additional cards M2, M3 and M4 similar to M' may be used, the total number of rows of plain terry tufts being equal to the product of the number of links in chain 144 multiplied by the number of cards M', M2, M3, etc. At each 65 complete rotation of the multiplier chain the low roll 145 will move under shoe 149 and the pawl 153 will fall momentarily to turn the cylinder 102 to feed the next multiplying card to active position.

70 The card following the last multiplying card will be blank in its upper right corner to prevent operation of the multiplier, and this condition will exist for all cards weaving the pattern following the plain area. One of these cards is 75 shown at P', Fig. 20.

From the foregoing it will be seen that I have provided a jacquard for weaving a three-pick terry wherein a single card can be provided for each row of terry tufts, each card corresponding to three successive beats of the loom. It will also be seen that inasmuch as the hooks which are to be engaged by knives 42 and 43 necessarily move together, an indication from the card at the beginning of the up motion of knife 42 suffices also as an indication at the beginning of the up motion of knife 43 and the cylinder can be moved out for a partial revolution to move the next card into indicating position during lifting of knife 43. It will also be seen that cam 90 is so made with the decline 112 as to relieve bending strains on the jacks after the time for indication and start of up motion of knife 41 has passed. The cams for controlling the knives and cylinder are symmetrical so that the jacquard may be set to run either in a forward direction 20 or be reversed. It will further be seen that provision is made for two separate three-pick motions kept in time by a shaft of the loom, one of these motions controlling the shift of position of the reed with respect to the lay, while 25 the other motion controls the lifting of the knives and the motion of the cylinder. Furthermore, provision is made for reversing the jacquard to permit a pick-out. It will also be seen that I have provided a jacquard for weaving terry fabric 30 so constructed that there may be combined with it a multiplier for the production of blank unfigured terry tufts area, this condition existing because of the fact that a single card suffices for the three-pick terry forming unit. 35

Having thus described my invention it will be seen that changes and modifications may be made therein by those skilled in the art without departing from the spirit and scope of the invention and I do not wish to be limited to the details 40 herein disclosed, but what I claim is:

1. In a jacquard mechanism for a loom to weave a terry fabric having successive three pick groups of weft, each group being formed in a cycle and the last weft of one cycle being in the same shed as the first weft of the succeeding cycle and having a warp to be in a given position for the first and third picks of a cycle and in the opposite position for the second pick of the cycle, a single card to control the position of the 45 terry warp for successive cycles, and means cooperating with the card and including three knives and mechanism to raise said knives one at a time and lift each knife during a pick of the loom to cause said terry warp to be in said 50 given position at the conclusion of the rising of the first and third knives and be in said opposite position at the conclusion of the rising motion of the second knife. 55

2. In a jacquard mechanism for a loom to weave a terry fabric having successive three pick groups of weft, each group being formed in a cycle and the last weft of one cycle being in the same shed as the first weft of the succeeding cycle and having a warp to be in a given position 60 on one pick of a cycle, in the opposite position on the second pick of the cycle and again in said given position on the third pick of the cycle, a single card to control the position of said terry warp for successive cycles, and means cooperating with said card and including three knives 65 and driving mechanism therefor to lift one knife for the first pick of the loom and lift the second knife for the second pick of the loom and lift the third knife for the third pick of the loom, any 70 75

two knives being moved to down position by said mechanism when the other knife is in high position, said means causing the warp to be in said given position at the conclusion of the rising motion of the first knife, to be in said opposite position at the conclusion of the rising motion of the second knife and to be again in said given position at the conclusion of the rising motion of the third knife.

3. In a jacquard mechanism for a loom to weave a terry fabric having successive three pick groups of weft, each group being formed in a cycle and the last weft of one cycle being in the same shed as the first weft of the succeeding cycle and having a warp to be in a given position for the first and third picks of a cycle and in the opposite position for the second of said three picks, a control shaft for the jacquard having a rotation once for every third pick of the loom, a card cylinder to be moved to indicating position with a single card in indicating position, means on the shaft to move the cylinder to indicating position every third pick of the loom to move the same card to indicating position for successive cycles, three separately movable lifting knives, means on the shaft to cause the knives to lift one at a time, one for each pick of the loom, and means controlled by the card and cooperating with the knives to place the warp in said given position at the end of the lifting motion of the first knife and place said warp in the opposite position at the end of the lifting motion of the second knife and place said warp again in said given position at the end of the lifting motion of the third knife, whereby a single card on the card cylinder controls the position of the warp for successive cycles of the loom.

4. In a jacquard mechanism for a loom to weave a terry fabric having successive three pick groups of weft, each group being formed in a cycle and the last weft of one cycle being in the same shed as the first weft of the succeeding cycle and having a warp to be given two weaving positions, three separately movable knives, means to give said knives a cycle of movements to be completed in three picks of the loom and during which each knife rises for one pick of the loom, a card cylinder carrying a card, means to present the cylinder and card to indicating position for every cycle of the loom, and means controlled by the card when in indicating position and actuated by the knives to place said warp in one position at the end of the rising motion of one of the knives and to place the warp in the other position at the end of the rising motion of the second knife and return the warp to the first position thereof at the end of the rising motion of the third knife.

5. In a jacquard mechanism for a loom to weave a terry fabric having successive three pick groups of weft, each group being formed in a cycle and the last weft of one cycle being in the same shed as the first weft of the succeeding cycle and having a warp to be given two different positions in each cycle, two jacks to control the position of the warp, a needle to control the jacks, a single card to position the needle and jack for the three picks of a cycle, means to raise one of said jacks to place the warp in one position for the first of said three successive picks and raise the other jack on the third of said three successive picks to place the warp in said one position, and the needle and means cooperating to leave both jacks unmoved to locate

said warp in the other position for the second of said three successive picks.

6. In a jacquard mechanism for a loom having a warp to be in a given position on the first pick of the loom, in the opposite position on the second pick of the loom and again in the given position on the third pick of the loom, a single card to control the position of the terry warp, and means cooperating with the card and including two lifting jacks one with a single hook and the other with a double hook and three independently moving knives, one for each hook, to place said warp in said given position when one of the knives has completed its lifting motion and to place said warp in the opposite position when the second knife has completed its rising motion and again place the warp in said given position when the third knife has completed its rising motion.

7. In a jacquard mechanism for a terry loom, three independently movable knives each having a cycle of movements extending through three successive picks of the loom and each knife to be moving up while another knife is descending and a third knife is dwelling in low position, a pair of terry warp controlling jacks one having one hook for one knife and the other jack having two hooks one for each of the remaining knives, a needle to position the jacks, a card to position the needle, means to move one of the knives up for the first pick and in engagement with one of the jacks to elevate the same, means to move the second knife up as the first knife descends and out of engagement with any hook to permit the first knife to lower the jack in engagement therewith for the second pick of the loom, means to raise the third knife to engage one of the hooks of the other jack to raise the same for the third pick of the loom, and means by which said jacks jointly control a terry warp thread.

8. In a jacquard mechanism for a loom, three knives, driving mechanism for the knives to lift the knives one at a time during a pick of the loom and requiring three successive picks of the loom to raise all three knives, said driving mechanism requiring one knife to rise while the second knife descends and the third knife remains at rest in low position, a pair of lifting jacks, a hook formed on one of the jacks to engage one of the knives, a pair of oppositely extending hooks on the other jack for engagement with the second and third knives, said second and third knives being separated by such a distance that one only of said knives can engage a hook of the second jack at a time, means to cause the jacks to have joint control of a warp, a needle to position both jacks simultaneously, and a single card to determine the position of the needle, said card and needle capable of positioning the first hook of the first jack for engagement with the first knife when the latter rises and causes the hooks of the second jack to be out of engaging position with the second knife when the latter rises during descent of the first knife and capable of causing one of the hooks of the second jack to be engaged by the third knife when the latter rises, said card and needle to cause the hook of the first jack and the hook of the second jack for engagement with the third knife to be out of engagement with their respective knives when the other hook of said second jack is positioned for engagement with the second knife.

9. In a jacquard mechanism for a loom having a warp to be raised one pick, lowered the next and raised the third, three lifting hooks for the warp, means to cause the warp to be raised when

- any hook is lifted, three lifting knives, one for each hook, means to lift the knives in consecutive order during a cycle of three consecutive picks of the loom, a knife being lifted for each pick of the loom, a card to control the hooks, means to move the card to controlling position relatively to the hook every third pick of the loom, and means cooperating with the card and controlling the hooks to place two of the hooks in position to be lifted by the first and third knives to rise during the cycle to raise the warp for the first and third pick of the loom, and said last means placing the second hook out of the path of the second knife to raise and thereby leave the warp in low position for the second pick of the loom.
10. In a jacquard mechanism for a terry loom having a reed with a three pick cycle the first two picks of which are beaten to a point spaced behind the fell while the third pick together with the other two are beaten to the fell, a pair of jacks for the jacquard both controlling a terry warp thread, one of said jacks having a single hook and the other jack having a double hook, three knives for the hooks each having a three pick cycle, means to raise each knife while another knife is descending and the third knife is dwelling in low position, a needle to control the jacks, a card to control the needle, and means to present the card to the needle once every third pick of the loom, said needle placing two of the hooks in lifting relation with respect to their corresponding knives and placing the third hook out of lifting relation with respect to its knife.
15. 11. In a jacquard loom for weaving terry fabrics, means requiring three successive picks of the loom to form a terry loop from a terry warp thread, two jacks both controlling the terry warp thread, one of said jacks having one hook and the other jack having two hooks, three lifting knives each having a cycle of three successive picks during which any knife rises for one pick, descends for the next pick, and dwells in low position for one pick, there always being one knife which is rising on each pick of the loom, a needle to control both jacks, a single card to control the needle, and mechanism having a three pick cycle to present the card to the needle every third pick of the loom, said needle to place the hook of said one jack and one of the hooks of the jack having the two hooks in the paths of their respective knives while the third hook is out of the path of its knife.
20. 12. In a jacquard mechanism for a loom having a warp to be raised for the first and third and be in low position for the second of three successive picks of the loom, a pair of warp lifting jacks one of which has one hook and the other of which has two hooks, three hook engaging jack lifting knives, means to raise one knife and lower the second knife and maintain the third knife in down position during a pick of the loom, the knives to be raised successively one at a time by said means and requiring three picks of the loom for a complete cycle of operations thereof, means to raise the warp when either jack is raised, the warp to be down when both jacks are in low position, a needle to determine the position of the jacks with respect to their respective knives, a card to control the position of the needle preparatory to the rising of the first and second knives, said card and means co-
25. operating to place the hook of the first jack out of the path of the first knife when the latter rises and acting to place one of the hooks of the second jack in the path of the second knife when the latter rises, means to move the card away from indicating position with respect to the needle subsequent to engagement by the second knife of the hook therefor, and said second knife and first hook of said second jack cooperating to hold the second hook of said second jack out of the path of the third knife when the latter rises while the card is out of indicating position with respect to the needle.
30. 13. In a jacquard mechanism for a terry loom to weave a terry fabric having successive three pick groups of weft, each group being formed in a cycle and the last weft of one cycle being in the same shed as the first weft of the succeeding cycle and having a terry warp to be raised on the first and third picks of each cycle and be in low position for the second pick of each cycle, said three picks constituting a terry forming cycle, a single card to control the position of the terry warp for the three picks of each cycle, means including three knives and mechanism to raise the knives one at a time and one for each pick of the cycle and in such order as to raise the terry warp on the first pick, lower said terry warp on the second pick and again raise the terry warp on the third pick, and a multiplier to maintain the card in control of the jacquard throughout a succession of three pick cycles of the jacquard.
35. 14. In a jacquard mechanism for a terry loom to weave a terry fabric having successive three pick groups of weft, each group being formed in a cycle and the last weft of one cycle being in the same shed as the first weft of the succeeding cycle and having a terry warp to be raised on the first and third picks of each cycle and be in low position on the second pick of each cycle, said three picks constituting a terry forming cycle, a series of cards, card feeding means to advance said cards to active position every third pick of the loom, mechanism between the cards and the terry warp including three knives to be raised one at a time and one for each pick of the loom together with mechanism controlled by the card and actuated by the knives to control the position of the terry warp, said knives and mechanism effective to raise the terry warp on the first pick of each cycle, lower said terry warp on the second pick of the cycle and again raise the terry warp on the third pick of the cycle, and multiplying mechanism controlling the first named means to arrest the feeding of the cards and maintain one card in active position throughout a period of successive three-pick cycles.
40. 15. A mechanism as set forth in the foregoing claim 13 wherein a part of the jacquard having a regular motion every third pick of the loom actuates the multiplier.
45. 16. A mechanism made according to claim 13 in which there is a controlling feed for the multiplying mechanism deriving its actuating force from a knife which is rising during the time that the card is in indicating position, whereby the feed mechanism for the cards is out of contact with the cylinder and therefore free to respond to the control exercised by said knife.
